UNITED STATES PATENT OFFICE.

CLARENCE S. MOODY AND WILLIAM OEPTS, OF ST. LOUIS, MISSOURI, ASSIGNORS TO HARRY L. GRIESEDIECK, OF ST. LOUIS, MISSOURI.

APPARATUS FOR MAKING PHOTOGRAPHIC FILMS.

Application filed July 11, 1924. Serial No. 725,492.

To all whom it may concern:

Be it known that we, CLARENCE S. Moody and WILLIAM OEPTS, citizens of the United States of America, and residents of the city 5 of St. Louis and State of Missouri, have invented certain new and useful Improvements in Apparatus for Making Photographic Films, of which the following is a full, clear, and exact description, reference 10 being had to the accompanying drawings, forming a part of this specification.

This invention relates generally to apparatus for and methods of making photographic film, and particularly to an apparatus of the type mentioned, which is so constructed and arranged that a film base may be handled in a manner to permit of the application to both surfaces thereof in a single operation of sensitive or insensitive 15 emulsions. The invention realizes its greatest utility in the making of all sensitized photographic film which is used in a flat condition where it is essential, or at least desirable that it should be absolutely flat 20 when in use. It is well known that for certain purposes photographic films are made in individual sheets of a size suitable for use. These films are used in a flat condition, and prior to this invention it was practically impossible to obtain films which would 25 lie absolutely flat. The reason that these films would not lie flat resulted from the fact that said films were coated with an insensitive emulsion on one surface only and 30 this caused buckling of said films. The present invention contemplates application to both surfaces of the film base of coatings of emulsion, whereby the tendency of said films to buckle as described is eliminated.

40 In making photographic film with our improved apparatus we may coat both surfaces of the film base with a sensitive emulsion. This would be done in the case of film for X-ray purposes, which is made 45 more effective by a sensitive coating on both sides; or we may provide the film base with a sensitive coating on one of its surfaces and an insensitive coating on its other surface. In the latter case the insensitive coating is 50 only applied for the purpose of off-setting the tendency of the single sensitive coating to cause the film base to buckle.

Another object of the invention is to produce an apparatus of the class described, 55 which is provided with means adapted to

tension or stretch the base material in both directions during the whole process of coating and drying, and thereby produce a finished film which is as flat practically as plate glass.

60 Still another object of our invention is to produce a film making apparatus which is provided with means for inspecting the finished film and also means for cutting the finished film to produce individual films of any desired sizes.

While the apparatus disclosed herein finds its greatest utility in the making of films in individual sheets, it is to be understood that roll film may be made thereon, and because 71 of the arrangement of said apparatus, the necessity of festooning the strips of which the roll films are composed to permit same to dry is eliminated.

75 With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

80 Fig. I is a diagrammatic view of our improved film-making apparatus, showing the manner in which the film base passes through the apparatus.

85 Fig. II is a fragmentary vertical section of the feeding end of the apparatus.

Fig. III is an enlarged fragmentary view partly in side elevation and partly in section, showing the feed rolls of the apparatus.

90 Fig. IV is a fragmentary vertical section of the end of the apparatus opposite to the feeding end thereof.

Fig. V is a fragmentary side elevation, showing the means for driving the feeding 100 rolls.

Fig. VI is a plan view of the feeding end of the apparatus, a portion of the supporting arm of one of the bearings which supports the upper feed roll being broken 105 away.

Fig. VII is a horizontal section showing the manner in which the film base is gripped by the gripping device associated with the sprocket chains.

Fig. VIII is an enlarged fragmentary perspective showing the gripping device associated with the sprocket chains, together with the means whereby said gripping device is caused to open.

Fig. IX is a cross section on line IX—IX of Fig. VIII.

Fig. X is a fragmentary perspective showing the mechanism for shifting the roll of film base to obtain the proper alinement thereof.

Fig. XI is a cross section on line XI—XI of Fig. VI.

Fig. XII is a cross section on line XII—XII of Fig. VIII.

In the drawings, A designates our improved film-making apparatus which is provided with a member 1, on which a roll of film base B is mounted, said film base usually being formed of a transparent material such as celluloid. The apparatus is provided with a suitable frame and the member 1 is supported by said frame in any desirable manner. The apparatus A is provided with a housing C, which is of a peculiar shape, said housing having the general shape of a reversed letter S. The housing C is divided into several compartments, the upper one, which is designated by the reference character D, being the setting chamber of the apparatus and the intermediate and lower portions of said housing comprising a drying chamber E. To provide for the circulation of air through the drying chamber E we provide said chamber with an air inlet passageway F and an air outlet passageway G (Fig. I).

Supported by the frame of the apparatus in any convenient manner is a plurality of rotatable shafts 2, 3, 4, 5 and 6, and arranged on each of the shafts 3, 4, 5 and 6 is a pair of smooth wheels which are designated by the reference characters 3', 4', 5' and 6'. The smooth wheels which comprise the pair of wheels on any one of the shafts mentioned are spaced apart from each other. In other words, said smoothed wheels are located adjacent to the opposite ends of said shafts. Mounted on the shaft 2 is a pair of toothed wheels 2', which, like the smooth wheels, are spaced apart from each other. All of the smooth wheels at one side of the apparatus and the toothed wheel at that side of the apparatus are in alinement with each other, and arranged to operate over the sets of alined wheels is a pair of endless sprocket chains 7. From the foregoing it is plain that there is a sprocket chain at each side of the apparatus and that said sprocket chains pass over the wheels 5', then rearwardly through the upper portion of the setting chamber C and around the wheels 4', then forwardly through the lower portion of said setting chamber and around the wheels 2' and then rearwardly through the

upper portion of the drying chamber and around the wheels 3' and then forwardly through the lower portion of the drying chamber and around the wheels 6' to the wheels 5'. The toothed wheels 2' on the shaft 2 constitutes the means for driving the sprocket chains 7 and it is apparent that when said chains are in operation they will travel through the S-shaped housing of the apparatus, as indicated by the arrows in Fig. I.

Arranged on the innermost face of each of the sprocket chains 7 is a plurality of gripping devices 8. These gripping devices each comprise a pair of jaws 9 and 10, the jaw 9 being stationary with respect to the link with which it is associated, said jaw preferably being an integral part of the associated link of the sprocket chain and the jaw 10 being pivotally secured to said jaw 9. Associated with each of the pivoted jaws 9 is a spring 11, which is so arranged that it tends to close the jaws 9 and 10. Each of the pivoted jaws 10 of the gripping devices is provided with a portion 10', which extends outwardly from said jaw, said portion being for a purpose to be hereinafter set forth.

Arranged adjacent to the wheels 5' is a pair of stationary curved bars 12 which are secured in any suitable manner to the frame of the apparatus. There is one of the curved bars located adjacent to each individual wheel 5', and said bars are so arranged and shaped that as the sprocket chains 7 move over the wheels 5' the projecting portions 10' associated with the pivoted jaws 10 will move under and behind said bars 12. It will be noted that each of the bars 12 is provided with an end portion 12' which curves inwardly toward the center of the apparatus. The location and shape of these curved portions 12' is such that the projecting portions 10' on the pivoted jaws of the traveling gripping devices will pass under and behind said curved portions 12' of the bars 12, and because of the curvature of said portions of the gripping portions of the pivoted jaws 10 will be caused to move away from the gripping portions of the stationary jaws 9 as shown in Fig. IX. During the period that the various gripping devices are passing the curved bars 12 the jaws are retained in an open position, but as soon as any one of said gripping devices has passed beyond one of said curved bars the spring 11 associated therewith will cause said jaws to be closed. It will be apparent from this that the jaws of the various gripping devices are retained in a closed position at all times by the springs 11, except when the projecting portions 10' contact with the curved bars 12, when said jaws will be open. Located adjacent to the wheels 6' is a pair of station-

ary curved bars 14 which are similar to the bars 12 already described. The bars 14 are so shaped and arranged that the jaws 9 and 10 of the gripping devices will be opened by said bars, as already described in connection with the bars 12.

As already stated, the film base material is arranged in a roll and said roll is mounted on a member 1. The strip of film base material passes from the roll over the roller 15 and then along the bed member 16 of the machine to the feed rolls 17 and 18, between which said strip of material passes. It will be remembered that the gripping devices on the sprocket chains 7 are in an open position when said gripping devices are passing over the wheels 5'. Consequently, the feed rolls 17 and 18 may draw the base material along the bed member 16, independently of said gripping members. However, as soon as the strip of base material reaches a point which is beyond the curved bars 12, the jaws of the various gripping devices will snap together and grip said strip of base material, and as a result the sprocket chains 7 carry the strip of base material with them as they pass through the housing C of the machine. When the film base material has completed its passage through the housing C of the apparatus it reaches a point adjacent to the wheel 6', where the jaws of the gripping devices are again opened, this time by the curved bars 14, and said strip of base material is permitted to again move independently of the sprocket chains.

Located at a point which is between the feed rolls 17 and 18 and the point where the strip of film base material enters the housing C of the apparatus, is an apparatus 20 by means of which sensitive or insensitive emulsions are spread on the upper surface of the strip of film base material. The apparatus 20 may be of any suitable type, the one illustrated in the drawing comprising a reservoir 21, a tube 22, a perforated member 23, a spreader 24 and a valve 25 for controlling the flow of liquid from the reservoir 21 to the perforated member 23. As the strip of base material passes beneath the apparatus 20, emulsion flows from the perforations in the member 23 onto the upper surface of said strip. The strip, of course, is moving at this time and it passes beneath the spreader 24, whereby the emulsion is distributed over the entire surface of the strip in the form of a thin coating.

After the emulsion has been applied to the upper surface of the strip as described, said strip passes into the setting chamber D of the apparatus. The setting chamber D is provided with a plurality of pipes 26, through which a cooling fluid, such as ammonia, passes. During the passage of the film base from the setting chamber D the

coating of emulsion placed on said film base of the apparatus 20 becomes set through the action of the cooling fluid in the pipes 26. When the strip of film base reaches the rear-most end of the setting chamber D, said strip passes around the wheels 4' and then moves in a forwardly direction. This has the effect of inverting the film base. In other words, it presents the uncoated face of the film base, which was the lowermost 75 face as said film base entered the setting chamber, uppermost.

Arranged within the setting chamber, between the first and second flights of the strip of base material, is a second emulsion-spreading apparatus 27. The emulsion-spreading apparatus 27 is an exact counterpart of the spreading apparatus 20 already described, there being a reservoir 28, a tube 29, a perforated member 30 and a spreading member 31. As the strip of base material passes beneath apparatus 27 emulsion is deposited on the uncoated face of said strip, and as said strip continues to move relative to the spreading member 31, said emulsion 90 will be distributed to form an even coating on said strip.

It is now plain that after the strip of base material has passed the second emulsion-spreading apparatus 27 it is provided 95 with a coating of emulsion on both of its surfaces, and said strip is then passed into and through the drying chamber E. As already stated, the drying chamber is provided with an air inlet and an air outlet, 100 and during the passage of the strip of base material through said drying chamber air is caused to pass through said drying chamber for the purpose of drying the coatings on the strip of base material. 105

It will be remembered that the curved bars 14 are located adjacent to the wheels 6' and it is therefore plain that as the various gripping devices approach said wheels 6' the jaws will be opened to release the strip of 110 base material. This will permit the strip of base material to continue in a straight line and the chains to travel upwardly toward the wheels 5', as shown in Figs. I and II.

Located adjacent to the wheels 6' is a receptacle 30' containing a plurality of light-producing elements, such as electric light bulbs 31'. The receptacle 30' is open at the top so that the electric light bulbs 120 may cast light rays through the strip of film, thus permitting said strip of film to be inspected. It is, of course, apparent that the electric light bulbs 31' will be of a color which will not injure the sensitized film. 125

H designates a cutting mechanism which may be of any suitable type, said cutting mechanism preferably comprising a stationary die member 32 and a periodically actuated die member 33. In operation the 130

disk 34, which is operated in synchronism with the movement of the strip of film, periodically depresses the movable die member 33 to cut individual sheets from the strip 5 of film, the remainder of the strip of film being wound on the roll 35, as shown in Figs. I and II.

In the operation of our improved film-making machine it is of the utmost importance that the strip of base material B be taut during the coating and drying operations, and to cause the strip of base material to be drawn tightly in a lateral direction we employ a pair of trackways 36 through 10 which those portions of the sprocket chains 7 which are for the time being located between the feed rolls 17 and 18 and the setting chamber D pass. The trackways 36 are rectangular in cross section and are each 15 provided with a slot 36' which extends from end to end of said trackway, through which slot the jaws 8 of the gripping devices extend (Fig. VII). By referring to Fig. VI it will be seen that the oppositely disposed 20 trackways 36 are closer together at the feed rolls than they are immediately adjacent to the setting chamber D. As has already been explained, the gripping devices grip the strip of base material immediately as it 25 leaves the feed rolls. The distance between the oppositely disposed sprocket chains is then gradually increased, due to the fact that said chains are traveling in the trackways 36, which diverge from each other as 30 they approach the setting chamber D, and as a result of this the strip of base material is stretched in a lateral direction as it moves toward said setting chamber. The chains 7 are arranged to travel through trackways 37 35 which extend through the entire housing C of the apparatus, which trackways are similar to and in continuation of the trackways 36. It is apparent, in view of this, that the lateral spacing of the chains is maintained 40 through the apparatus, whereby the strip of base material is maintained in a taut condition throughout its passage through the apparatus. It is, of course, apparent 45 that the trackways 37 within the housing C are spaced the same distance apart as are the trackways 36 at their widest point.

To cause the strip of base material to be drawn tightly in a longitudinal direction we provide means for actuating the feed rolls 50 55 17 and 18, which is so arranged that said feed rolls have a peripheral speed, which is relatively slower than the speed at which the sprocket chains move. This results in a dragging or holding back on the part of 60 the feed rolls, whereby the strip of base material is drawn taut as it passes into the setting chamber D. The means for causing the feed rolls to rotate at a relatively low rate of speed as compared with the speed of 65 the sprocket chains comprises a pulley 39

on the feed shaft 2 of the apparatus and a pulley 40 which is supported by the frame of the machine at a point adjacent to the feed rolls 17 and 18. A belt 41 is arranged to operate over said pulleys 39 and 40 so 70 that movement is transmitted from said pulley 39 to said pulley 40. Mounted on the shaft on which the pulley 40 is mounted is a sprocket wheel 42, and mounted on the shaft on which the feed roll 18 is mounted is a larger sprocket wheel 43. Arranged to travel over the sprocket wheels 42 and 43 is a sprocket chain 44, by means of which rotary movement is transmitted to said feed roll 18. The shafts on which the feed rolls 17 and 18 are mounted are provided with pinions (Fig. V), whereby motion is transmitted from one of said shafts to the other. From the foregoing it is plain that, in view of the relatively large sprocket wheel 43 on the shaft on which the feed roll 18 is mounted, said feed roll will be rotated at a rate of speed which is relatively less than the rate of speed at which the sprocket chains 7 travel.

To provide means whereby the strip of base material may be guided, we employ means illustrated in Fig. X whereby the roll of base material may be shifted laterally of the apparatus, said means comprising a vertically arranged oscillatory shaft 50 provided with a member 51 at its lower end, having a bifurcated portion which extends into an annular groove formed in the collar 52. The collar 52 constitutes a part of the member 53 on which the roll of film base material is wound and said member 53 is movable longitudinally of the shaft 1 on which it is mounted. 54 designates an operating lever which is attached to the upper end of the vertical shaft 50, and 55 designates a toothed segment, which is adapted to retain the lever 54 in any desired position. It is apparent from the foregoing that by moving the outer end of the operating lever 54 in an arc of a circle the member 53 may be moved along the shaft 1 to guide the strips of base material being drawn therefrom and to properly align said strip with respect to the apparatus.

As an additional means for guiding the strip of base material, as it leaves the roll on which it is wound, we employ a bar 56 which is pivoted to the frame of the machine at the point designated by the reference character 56'. The bar 56 is L-shaped in cross section and is arranged in such position on the machine that an edge of the strip of base material contacts with a face of said bar as said strip moves toward the feed rolls. The frame of the machine is provided with an upstanding lug 57, which is located adjacent to the pivoted bar 56, and a threaded member 58 passes through a threaded opening in said lug. The threaded

member 58 bears against the pivoted bar 56, as shown in Fig. VI, and it is plain that the course of the strip of base material may be altered by manipulating the threaded member 58 to change the position of the pivoted bar 56.

As has been stated, the shaft on which the feed roll 17 is mounted is arranged in bearings, and to assist in guiding the strip of base material in its proper course we provide means whereby said shaft may be moved vertically at one of its ends to increase the pressure on the strip of base material at that point. This means comprises a shoe 59 (Fig. III) arranged above said shaft and a vertically movable threaded member 60 which passes through a threaded opening in the bearing and bears against said shoe 59. Located below the shaft is a coil spring 61 which is interposed between a shoe 62 and a fixed member 63 at the lower end of the bearing. It is apparent from the construction shown in Fig. III that by rotating the threaded member 60 to cause same to move downwardly, the pressure of the roll 17 on the strip of base material will be increased at the end of said feed roll which is adjacent to the adjusting mechanism just described. It is also plain that by causing the threaded member 60 to move upwardly the pressure of the feed roll on the strip of base material will be decreased as the coil spring 61 will move said feed roll upwardly. By manipulating the adjusting mechanism just described to increase or decrease the pressure of the feed roll at the edge of the strip of base material, it is apparent that the path of travel of said strip of base material will be altered.

40 We claim:

1. In an apparatus for making photographic film, means whereby motion is imparted to a strip of base material, means whereby a coating of emulsion is applied to one surface of the moving strip of base material, a setting chamber through which said coated strip of base material passes, means whereby a coating of emulsion is applied to the other surface of said moving strip of base material, and a drying chamber through which said strip of material passes to dry said coatings of emulsion.

2. In an apparatus for making photographic film, means whereby motion is imparted to a strip of base material, means whereby a coating of emulsion is applied to one surface of the moving strip of base material, a setting chamber through which said coated strip of base material passes, means within said setting chamber whereby a comparatively low temperature is maintained therein, means whereby a coating of emulsion is applied to the other surface of said moving strip of base material, and a drying chamber through which said strip of

material passes to dry said coatings of emulsion.

3. In an apparatus for making photographic film, means whereby motion is imparted to a strip of base material, means whereby a coating of emulsion is applied to one surface of the moving strip of base material, a setting chamber through which the coated strip of base material passes, means within said setting chamber whereby a comparatively low temperature is maintained therein, means whereby a coating of emulsion is applied to the other surface of said moving strip of base material and a drying chamber through which said strip of material passes to dry said coatings of emulsion, said drying chamber being provided with means adapted to permit a current of air to pass through said drying chamber.

4. In an apparatus for making photographic film, flexible traveling means provided with gripping jaws adapted to grip a strip of base material whereby said strip of base material is caused to travel with said flexible traveling means, means whereby a coating of emulsion is applied to the uppermost surface of said strip of base material while said strip is in motion, means whereby the course of travel of said flexible traveling means is directed in a manner to invert the strip of base material, and means whereby a coating of emulsion is applied to the uncoated surface of said moving strip of base material.

5. In an apparatus for making photographic film, flexible means provided with gripping jaws adapted to grip a strip of base material, whereby said strip of base material is caused to travel with said flexible traveling means, means whereby a coating of emulsion is applied to the uppermost face of said strip of base material, a setting chamber through which said coated strip of base material passes, said setting chamber being provided with means whereby a comparatively low temperature is maintained therein, means whereby the course of travel of said flexible traveling means is directed in a manner to invert the strip of base material carried thereby and means whereby a coating of emulsion is applied to the uncoated surface of said strip of base material, and a drying chamber through which said coated strip passes to dry said coatings of emulsion thereon, said drying chamber being provided with an air inlet and air outlet to provide for a current of air therethrough.

6. In an apparatus for making photographic film, flexible traveling means provided with gripping jaws adapted to grip a strip of base material whereby said strip of base material is caused to travel with said traveling means, means whereby both surfaces of said strip of base material are provided with coatings of emulsion while said

strip is in motion and means whereby said strip of base material is drawn taut in longitudinal direction, said means comprising feed rolls arranged to rotate at a rate of speed which is relatively lower than the rate of speed at which said flexible means travel.

7. In an apparatus for making photographic film, flexible traveling means provided with gripping jaws adapted to grip a strip of base material, whereby said strip of base material is caused to travel with said traveling means, means associated with said traveling means whereby said strip of base material is drawn taut in lateral direction, means whereby said strip of base material gripped by said flexible traveling means is drawn taut in longitudinal direction, and means for applying a coating to said strip while it is so held in the taut condition.

8. In an apparatus for making photographic film, flexible traveling means provided with gripping jaws adapted to grip a strip of base material, whereby said strip of base material is caused to travel with said traveling means, means associated with said traveling means whereby said strip of base material is drawn taut in lateral direction, means whereby said strip of base material gripped by said flexible traveling means is drawn taut in longitudinal direction, said

means comprising feed rolls arranged to rotate at a rate of speed which is relatively lower than the rate of speed at which said flexible means travels, and means for applying a coating to said strip while it is so held in the taut condition.

9. In an apparatus for making photographic films, traveling means provided with gripping devices adapted to grip a strip of base material to cause said strip to travel with said traveling means, and means for applying coatings of emulsion to both surfaces of the strip of base material while said strip is held by said gripping devices and caused to travel with said traveling means.

10. In an apparatus for making photographic film, traveling means provided with gripping jaws adapted to grip a strip of base material to cause said strip to travel with said traveling means, means for applying coatings of emulsion to both surfaces of the strip of base material while said strip is held by said gripping jaws and caused to travel with said traveling means, and means comprising curved bars for periodically opening said jaws.

In testimony that we claim the foregoing we hereunto affix our signatures.

CLARENCE S. MOODY.
WILLIAM OEPTS.

- strip is in motion and means whereby said strip of base material is drawn taut in longitudinal direction, said means comprising feed rolls arranged to rotate at a rate of speed which is relatively lower than the rate of speed at which said flexible means travel.
7. In an apparatus for making photographic film, flexible traveling means provided with gripping jaws adapted to grip a strip of base material, whereby said strip of base material is caused to travel with said traveling means, means associated with said traveling means whereby said strip of base material is drawn taut in lateral direction, means whereby said strip of base material gripped by said flexible traveling means is drawn taut in longitudinal direction, and means for applying a coating to said strip while it is so held in the taut condition.
8. In an apparatus for making photographic film, flexible traveling means provided with gripping jaws adapted to grip a strip of base material, whereby said strip of base material is caused to travel with said traveling means, means associated with said traveling means whereby said strip of base material is drawn taut in lateral direction, means whereby said strip of base material gripped by said flexible traveling means is drawn taut in longitudinal direction, said
- means comprising feed rolls arranged to rotate at a rate of speed which is relatively lower than the rate of speed at which said flexible means travels, and means for applying a coating to said strip while it is so held in the taut condition.
9. In an apparatus for making photographic films, traveling means provided with gripping devices adapted to grip a strip of base material to cause said strip to travel with said traveling means, and means for applying coatings of emulsion to both surfaces of the strip of base material while said strip is held by said gripping devices and caused to travel with said traveling means.
10. In an apparatus for making photographic film, traveling means provided with gripping jaws adapted to grip a strip of base material to cause said strip to travel with said traveling means, means for applying coatings of emulsion to both surfaces of the strip of base material while said strip is held by said gripping jaws and caused to travel with said traveling means, and means comprising curved bars for periodically opening said jaws.

In testimony that we claim the foregoing we hereunto affix our signatures.

CLARENCE S. MOODY.
WILLIAM OEPPTS.

Certificate of Correction.

It is hereby certified that the name of the assignee in Letters Patent No. 1,568,344, granted January 5, 1926, upon the application of Clarence S. Moody and William Oepts, of St. Louis, Missouri, for an improvement in "Apparatus for Making Photographic Films," was erroneously written and printed as "Harry L. Griesedieck," whereas said name should have been written and printed as *Henry L. Griesedieck*, as shown by the records of assignments in this office; and that the said Letters Patent should be read with this correction therein that the same may conform to the record of the case in the Patent Office.

Signed and sealed this 9th day of February, A. D. 1926.
